UNITED STATES PATENT OFFICE.

ANDREW LETKO, OF INDIANA HARBOR, INDIANA.

RAIL-JOINT FASTENER.

1,391,130.

Specification of Letters Patent. Patented Sept. 20, 1921.

Application filed June 8, 1921. Serial No. 475,929.

To all whom it may concern:

Be it known that I, ANDREW LETKO, citizen of Czechoslovakia, residing at Indiana Harbor, in the county of Lake and State of Indiana, have invented certain new and useful Improvements in Rail-Joint Fasteners, of which the following is a specification.

This invention relates to rail fastening devices for securing the railroad tracks to the ties or sleepers, and it has for an object to provide a novel form of rail fastener which will act to securely hold the rail and which permits of the ready removal of the rail when desired.

For further comprehension of the invention, and of the objects and advantages thereof, reference will be had to the following description and accompanying drawings, and to the appended claims in which the various novel features of the invention are more particularly set forth.

Figure 1 of the drawings is a plan view of a portion of a railroad track secured in place by means of my improved fastening devices.

Fig. 2 is a side view thereof.

Fig. 3 is an enlarged detail section on the line 3—3 of Fig. 1.

Fig. 4 is an enlarged detail section on the line 4—4 of Fig. 1.

Fig. 5 is an enlarged fragmentary plan view showing one of the fastening devices applied to a rail.

Fig. 6 is an enlarged detail section on the line 6—6 of Fig. 1.

Fig. 7 is a section on the line 7—7 of Fig. 5.

In the drawings the reference numeral 10 indicates a pair of track rails which rest on ties 11, the latter preferably comprising metal I-beams.

My improved fastening device, by means of which the rails are secured to the ties, comprises plates 12 which are secured by bolts 13 to the ties 11 and engage one side of the rail, having projecting toes 12' which take over the base flange of the rail.

The opposite side of the rail is adapted to be engaged by blocks 15 having toes 15' adapted to take over the base flange of the rail. These blocks 15 are slidably held between a pair of guide bars 16 fixed by bolts 17 to the ties 11, the inner ends of these bars 16 abutting against the base flange of the rail as shown. Formed on the blocks 15 and bars 16 are overlapping flange members

18 whereby the blocks are held from vertical displacement.

To secure these blocks 15 in position with their toes 15' engaging over the rail flange I 60 secure to the tie 11, underneath each of the blocks, a flat spring 20 which extends transversely of the rail, is riveted at one end as at 21' to the tie 11, being provided near its opposite end with a vertical offset 21 which 65 engages in an angular notch 22 on the bottom of the block 15 at the outer end thereof. The spring 20 is accommodated in a recess 11' in the tie. Beyond the offset 21 the spring 20 terminates in a tongue 23 which 70 inclines downwardly and outwardly to engage the outer upper corner of the recess 11' as shown, the notch 22 in the block 15 being correspondingly shaped so that access to the spring 20 from the outer end of block 15 is 75 prevented. Formed in the block 15, in registry with the notch 22, is an aperture 25 through which a rod or pin may be inserted to engage and depress the spring 20 and free it from the block 15. 80

As will be apparent in the assembly of the track, the plates 12 and bars 16 may first be bolted to the ties 11. The rail 10 is then inserted in place and the blocks 15 slid along the ties between the bars 16 until their toes 85 engage the base flange of the rail, the blocks riding over the springs 20 which automatically spring up to engage in the notches 22 and so lock the blocks against rearward movement. When the rails are to be taken 90 up a suitable instrument is inserted through the aperture 25, engaging tongue 23 on spring 20 and forcing the latter downward into the recess 11' until the offset 21 is clear of the block. 95

Having thus described my invention what I claim as new and desire to protect by Letters Patent of the United States is as follows:

1. A rail fastening device comprising a 100 plate adapted to engage one side of the base flange of the rail, a block adapted to engage the other side of the base flange of the rail, means guiding said block for movement transversely to the rail, and 105 means engaging behind the said block to hold the latter in position, said last means comprising a flat spring having an offset adapted to engage the block.

2. A rail fastening device including a tie 110 having a recess in its upper face, a plate secured to said tie and adapted to engage

one side of the base flange of the rail, a pair of guide bars secured to said tie on the opposite side of the rail, a slidable block between said guide bars and retained against 5 vertical displacement thereby, and adapted to engage the other base flange of the rail, said slidable block having a notch in its under side, and a flat spring located in the said recess in the tie and having an offset 10 adapted to engage in said notch.

3. A rail fastening device including a tie having a recess in its upper face, a plate secured to said tie and adapted to engage one side of the base flange of the rail, a pair of

guide bars secured to said tie on the opposite 15 side of the rail, a slidable block between said guide bars and retained against vertical displacement thereby, and adapted to engage the other base flange of the rail, said slid- 20 able block having a notch in its under side, and a flat spring located in the said recess in the tie and having an offset adapted to engage in said notch, said block having an aperture leading through the top thereof into said notch, for the purpose set forth. 25

In testimony whereof I have affixed my signature.

ANDREW LETKO.
